UNITED STATES PATENT OFFICE

168,685

INSECTICIDE VAPORIZER

Charles F. Holbrook, Harlingen, Tex., assignor to
Vaporette, Inc., Dallas, Tex., a corporation of
Texas

Application August 18, 1952, Serial No. 21,084

Term of patent 14 years

(Cl. D31—3)

To all whom it may concern:

Be it known that I, Charles F. Holbrook, a citizen of the United States of America, residing at Harlingen, State of Texas, have invented, a new, original, and ornamental Design for an Insecticide Vaporizer, of which the following is a specification, reference being had to the accompanying drawing, forming a part hereof.

Fig. 1 is a top plan view of an insecticide vaporizer, showing my new design,

Fig. 2 is a bottom plan view of the vaporizer,
Fig. 3 is a front elevation of the vaporizer,
Fig. 4 is a side elevation of the vaporizer.

I claim:

The ornamental design for an insecticide vaporizer, as shown.

CHARLES F. HOLBROOK.
